UNITED STATES PATENT OFFICE.

ABRAHAM POLLAK, OF FAR ROCKAWAY, NEW YORK, ASSIGNOR TO PENCIL MECHANISM CORPORATION, OF NEW YORK, N. Y., A CORPORATION OF NEW YORK.

MECHANICAL PENCIL.

Application filed January 20, 1927. Serial No. 162,272.

This invention relates to improvements in mechanical pencils, preferably of the magazine type.

Among the objects of this invention are, 5 to simplify the construction of pencils of this type and to enable the manufacture thereof more economically; to provide a pencil construction that can be readily and easily repaired and that can be assembled and 10 disassembled by unskilled persons without the use of tools; to provide in a refillable or mechanical lead pencil, feeding mechanism preferably embodying a gripping element composed of a plurality of fulcrumed gripping 15 members for moving a lead of small diameter in a step by step movement through the feed channel or pencil-bore without nicking or breaking the same; to provide feeding mechanism whereby the lead will be 20 positively gripped with a resilient pressure and any crushing or indentation of the lead will be avoided; to provide lead-feeding mechanism having a lead-gripping element embodying a plurality of longitudinally 25 split lead-encircling members preferably provided with arcuate lead-gripping surfaces arranged to close in parallel relationship to each other and thus to avoid unbalanced pressure on and breakage of the lead, while 30 procuring a positive engagement and gripping thereof; to provide a pencil construction in which the feeding of the lead is accomplished through frictional engagement of a resilient closing member with the lead- 35 gripping element and manual feeding pressure is applied to this gripping element through said closing element; to provide a mechanical pencil with reciprocating feeding mechanism operable to have at one end 40 of its reciprocating movement a quick and positive lead-gripping movement as opposed to a gradual lead-gripping movement and a positive and quick release of the gripping member at the other end thereof, thus avoiding 45 lost motion and avoiding the carrying back or recessional movement of the lead by the feeding mechanism, and consequently enabling a complete feeding movement of the lead on each reciprocating operation of the 50 feeding mechanism; to provide, in a mechanical pencil, a lead magazine having a reciprocating bottom portion preferably of plunger-like conformation, adapted to agi-

tate the lead in the magazine and thus to cause a more positive guiding and feeding 55 of the lead from the magazine into the feed channel or bore of the pencil; to provide a pencil construction in which a lead-gripping element is mounted to have a limited floating movement within the pencil casing and 60 a resilient closing element is movable automatically by a spring to carry the gripping element to one limit of its movement and then to resiliently engage said gripping element to cause a gripping thereby of the lead and a frictional locking engagement sufficient 65 to permit a manual lead-feeding movement of said gripping element to be applied through said resilient closing element; to utilize said plunger-like magazine bottom as 70 a guiding member for the gripping element in its reciprocating movement and to provide a fulcrum about which the lead-gripping members of the gripping element are adapted to rock into open and closed position upon 75 such reciprocation by the action of the closing and opening elements respectively.

With these and other objects in view, the invention comprises the combination of members and arrangement of parts so combined 80 as to coact and cooperate with each other in the performance of the functions and the accomplishment of the results herein contemplated, and comprises in one of its adaptations the species or preferred form illustrated in the accompanying drawings, in which:

Fig. 1 is a longitudinal section of a pencil embodying my invention;

Fig. 2 is an enlarged section similar to Fig. 1 of the lower portion of the pencil, showing the parts of the feeding mechanism in initial lead-gripping position;

Fig. 3 is a view similar to Fig. 2 showing the feeding mechanism with the parts depressed just prior to release of the lead by the gripping element;

Fig. 4 is a longitudinal section similar to Figs. 2 and 3, showing the parts of the feeding mechanism further depressed to completely release the gripping element from the lead;

Figs. 5 to 8 are a series of cross sections on the lines 5-5, 6-6, 7-7, and 8-8 respectively of Fig. 2, looking in the direction of the arrows;

Fig. 9 is a view, in elevation, of the lower portion of the operating tube removed from the casing and sectioned to show the gripping and closing members of the feed mechanism;

Fig. 10 is a perspective view of the agitating bottom portion of the magazine section; and

Fig. 11 is a perspective view of the internal surface of the lead-gripping element of my feed mechanism.

Referring now to these drawings, which illustrate a preferred embodiment of my invention, C indicates an outer casing having at its lower end a tapered tip c which, as shown, is connected to the casing C by interengaging screw-threads t. Said tip c has at its lower end a lead channel or bore b' of substantially the diameter of the leads 20 to be used, which communicates with a bore b of increased diameter, which in turn communicates with a casing bore B of still greater diameter.

Mounted in stationary position within the bore b of the tip c, I preferably provide a lead-guiding tube 1 having a bore registering with the bore 1^a and provided at its lower end with a split portion adapted to provide resilient lead-guiding jaws 2 surrounding said bore 1^a, having an upper portion 1^b projecting upwardly into the casing-bore B and provided with a sharpened or tapered end 1^c arranged as hereinafter described to act as an opening element for the lead-gripping element of the feed mechanism.

Mounted within the casing-bore B above the opening and guiding element 1, I provide lead-feeding mechanism for moving the lead in a step by step movement through the channel or lead bore 1^a in the guiding member 1 and through the bore b' in the lower end of the tip portion of the casing C, said feeding mechanism being adapted to so feed a lead of small diameter without nicking or breaking the same. It is obvious that in feeding leads of small diameter a relatively large surface of the lead, both circumferentially and longitudinally should be gripped, and it will be understood that space within the bore of a pencil is extremely limited and the gripping element must be relatively small. In order to provide a gripping element of the required small size which will act quickly and positively to grip and release the lead, which will have the necessary accuracy with which this part must be formed, and which may be readily and quickly assembled, both initially and for repairs, I have provided a gripping element composed of a plurality of parts fulcrumed to swing or rock from gripping to non-gripping positions and vice versa upon reciprocating movement of such element and, as shown, I provide a gripping element 10 com-

posed of two semi-cylindrical parts 10', 10^a and having semi-cylindrical gripping surfaces 10^e and I mount said two cylindrical parts on a fulcrum suitably guided within the casing. As illustrated, a guiding member 12 carries at its lower end a depending fulcrum portion 15 which extends into a split bore 10^b formed between the parts 10', 10^a. Said fulcrum portion 15 is provided at its lower end with a fulcrum 15' which seats in a fulcrum-seat 10^c at the lower end of the bore 10^b of said parts 10', 10^a, said bore 10^b embracing the fulcrum portion 15, (see particularly Figs. 10 and 11), and said guiding member and fulcrum portion are provided with a continuous axial lead-channel or bore 13' communicating at its upper end with a magazine section 14 as hereinafter described, and at its lower end with a middle bore 10ⁱ of reduced diameter, which is again reduced to form the lead-gripping surfaces 10^e. These surfaces 10^e may, if desired, be roughened or provided with teeth so as to procure a better grip on the leads L as they pass through the continuous bore 13' from the magazine to the bores 10^a and 10^c of the gripping element 10. The gripping element is thus composed of two semi-cylindrical parts 10', 10^a, having semi-cylindrical gripping surfaces 10^e, and the said two cylindrical parts 10', 10^a are mounted on the plunger member 12 to swing about the fulcrum 15' so as to enable contact with and release from the leads L, it being understood that the upper end of the guiding member 12 forms the bottom of the magazine section and this upper end is provided with a depressed conical surface 13^a leading to the bore 13' which in turn communicates at its other end with the middle bore 10ⁱ of the gripping member.

This floating gripping element 10 is, in accordance with my invention, reciprocated and actuated to grip and release the lead, and preferably the lead will be positively gripped with a resilient pressure which will avoid any crushing or indentation thereof, and, to this end, my improved mechanism is caused at one end of its reciprocating movement to have a quick and positive lead-gripping movement, while at the other end of its reciprocating movement, this resilient grip will be instantaneously released, thus causing a feeding movement of the lead which will be complete, without any recession of the lead. In the preferred embodiment of my invention shown, the two parts 10', 10^a of the lead-gripping element are preferably held together by a band 11 which is preferably formed of resilient wire fitting into grooves 11^a in the perimeter of the gripping element 10. Said gripping element 10 is preferably mounted on the guiding member 12, as above described, to have a limited floating movement therewith within the bore B of the casing and, as illustrat-

ed, said floating element 12 is of plunger-like construction having its upper end arranged to close and form a bottom for the magazine compartment 13 formed at the upper end of the tube 14. The element 12 is guided in its floating movement by the provision of oppositely-extending guide lugs 12' and 12^a extending within oppositely-disposed slots 14', 14^a in an inner actuating tube 14, the upward movement of said element 12 and that of the gripping element carried thereby, being limited by engagement thereof with the lower end 19' of a relatively stationary outer tube 19 mounted within the casing C.

The gripping element 10 is thus guided and floats with its guiding member 12 within the bore 14^b of the actuating tube 14. Said tube 14 preferably has a closing element 16 releasably connected thereto at its lower end. This is accomplished by the provision on said tube 14 of integral lugs 14^c fitting into a groove 16' in said closing element 16, the connection being covered by a collar 16^a. Said closing element 16 has at its lower end a spring-guiding hub 16^b. Said closing element 16 is also provided with upwardly-directed resilient arms 17 adapted to encircle the lower end of the gripping element 10 and to move the same inwardly by spring pressure when these resilient split arms 17 are moved upward. As illustrated, the arms 17 are provided with internally-tapered guiding surfaces 17' which are arranged to contact with the externally-tapered surfaces 10^c at the lower end of the gripping element 10. In the preferred embodiment shown, the upward stroke of the longitudinal reciprocating movement initially moves the element 10 to its uppermost limit of movement and power for this purpose is provided by means of a spring 18 arranged to encircle the lead-guiding member 1 and to abut at one end against the bottom of the bore B and at the other end against the lower end of the closing element 16 which is connected, as aforesaid, to the tube 14. The pressure of the spring 18, thus acting through the closing element 16 having the spring arms 17, forces the gripping element 10 and plunger 12 up to their uppermost limit of movement, which upward movement, as aforesaid, is limited by contact with the lower end 19' of the outer tube 19. The gripping element is thus carried upwardly in open position, the spring 11 keeping the parts open until this upper limit of its floating movement is reached, no closing or gripping action taking place during such movement, but when such upward limit of movement of the gripping element is reached, the spring 18 continues to move the closing element 16 upwardly until the resilient arms 17 engage and apply resilient pressure radially on the

lower end of the said gripping element 10, thus forcing the lead-gripping surfaces 10^c into firm though resilient contact with the lead. It will be seen that this closing movement takes place only after the floating gripping element is carried upwardly to its full limit of reciprocating or longitudinal movement; that the movement is purely radial without any accompanying longitudinal movement and can, therefore, have no reTRACTING or recessional effect on the lead, and it will also be seen that the members 10', 10^a of the gripping element are rocked on the fulcrum and close in parallel relationship to each other to cause uniform though resilient gripping pressure on the lead.

It will be noted, furthermore, that when the closing element 16 so engages the gripping element 10, a frictional contact therebetween will be made which will enable a feeding of the lead by a manual movement of said frictionally-engaged closing element and in the preferred embodiment shown, I procure a feeding of the lead by manual pressure on the tube 14 applied at its upper end. This may be accomplished in any well-known way and, as shown, the tube 14 is provided at its upper end with a lead-receiving cup 20 over which is fitted a cap 21. A collar 20' at the lower end of the cup 20 is arranged above an enlarged threaded collar C' having a screw-threaded connection at C² with the casing, and the tube 14 reciprocates through the bore 20^a of this collar C'.

The lead being gripped, as aforesaid, manual pressure on the cap will be transmitted through the cup 20 and the tube 14 against the pressure of the spring 18, and through the frictional engagement, as aforesaid, of the resilient arms 17 with the gripping element 10, the lead may be fed downwardly in the lead-bore or channel through the various elements. The longitudinal or reciprocating manual movement of the gripping element so embraced and held in closed lead-gripping position by the arms 17, is limited by direct contact thereof with the upper end 1^c of the guiding tube 1, and release of the lead is thus effected after longitudinal movement of the gripping element 10 and the consequent feeding movement of the lead has completely stopped. There, is therefore, no additional feeding movement of the lead, however slight, during the opening movement of the gripping element, complete opening of the gripping element to release the lead being effected by the further or additional releasing movement of the closing element. The extent of the feeding movement will thus be positively defined and limited at opposite ends because such movement of the feeding element is directly limited before any closing or opening takes place, both gripping and release of the lead being accomplished by the continuance of the

stroke of the closing element beyond opposite ends of the stroke of the lead-gripping element.

As shown, the outer surface of this tube 5 1 forms a guide on which the closing member 16 is mounted to reciprocate, said tube, as shown, passing through a bore 16^c of said member 16 and engaging the gripping element 10 to limit its stroke, and further 10 manual pressure applied through the tube 14 on the element 16 against the pressure of the spring 18, will cause an additional movement of said closing member and will release the spring arms 17 of the closing element 16 from engagement with the gripping element 10. The position of the parts are such that immediately upon the limiting or stopping engagement of the gripping element, the pointed or tapered end 1^c of the 15 limiting stop thereof will force open the jaws and fully release the lead as illustrated in Fig. 4, this insertion of the tapered end 1^c occurring immediately after the release of the gripping member from engagement by 20 the additional downward movement of the closing member 16. Upon release of the manual pressure, the spring 18 will immediately act to restore the parts to their initial position hereinabove described, the floating 25 gripping element 10 and plunger member 12 being pushed upwardly by the spring-pressed closing member 16 until such floating members reach their upward limit of movement upon the engagement of the guide 30 lugs 12', 12^a with the lower end 19' of the tube 19, whereupon the closing member having a longer stroke also in the upward movement will cause the members 10', 10^a to be swung by the action of the spring arms 17 on the fulcrum 15' to fully close on the lead, 35 said resilient arms 17 moving into the position shown in Fig. 2, so as to provide a frictional engagement with the lower end of said gripping element, as aforesaid.

40 The operation of the device and its several parts will be clear from the foregoing description.

Having described my invention, I claim:—

1. A mechanical lead pencil embodying a 45 casing having at its lower end a tapered tip provided with a lead channel, a lead-gripping element mounted to reciprocate within the casing and composed of a plurality of members rockable on a fulcrum also mounted within said casing, and means for rocking said members on the said fulcrum at opposite ends of said reciprocating movement to alternately grip and release the lead to feed the same in a step by step movement 50 through said lead channel.

2. A mechanical lead pencil embodying a 55 casing having at its lower end a tapered tip provided with a lead channel, a lead-gripping element mounted to reciprocate within the casing and composed of a plurality of 60

members rockable on a fulcrum also mounted within said casing to reciprocate with said gripping element and means for rocking said members on the said fulcrum at opposite ends of said reciprocating movement to alternately grip and release the lead to feed the same in a step by step movement through said lead channel. 70

3. A mechanical lead pencil embodying a casing having at its lower end a tapered tip 75 provided with a lead channel, a member mounted to reciprocate within said casing and provided with a fulcrum, a lead-gripping element reciprocable with said fulcrum member and composed of a plurality of 80 members rockable on said fulcrum, and means for causing the rocking of said gripping members on said fulcrum at opposite ends of said reciprocating movement to alternately grip and release the lead to feed 85 the same in a step by step movement through said lead channel.

4. A mechanical lead pencil embodying a casing having at its lower end a tapered tip provided with a lead channel, a lead-gripping element mounted to reciprocate within the casing and composed of a plurality of members rockable on a fulcrum also mounted within said casing, a closing element for 90 rocking said members on said fulcrum to close at one end of said reciprocating movement, means for moving said two gripping and closing elements together in an engaged lead-feeding movement, and means for stopping the movement of one of said elements 95 before the other to release the lead. 100

5. A mechanical lead pencil embodying a casing having at its lower end a tapered tip provided with a lead channel, a lead-gripping element mounted to reciprocate within 105 the casing and composed of a plurality of members rockable on a fulcrum also mounted within said casing, a closing element having a plurality of resilient arms for rocking said members on said fulcrum to close at one 110 end of said reciprocating movement, means for moving said two gripping and closing elements together in an engaged lead-feeding movement, and means for limiting the movement of the gripping element to a shorter stroke than the closing element to release the lead. 115

6. A mechanical lead pencil as claimed in claim 5, in which the resilient closing element is movable by spring pressure into frictional engagement with said gripping element and means is provided for exerting manual pressure on the closing element to reciprocate the closing and gripping elements together to move the lead and feed it 120 through the tip. 125

7. In a mechanical lead pencil casing having a centrally-disposed lead channel and an enlarged magazine section above said channel and communicating therewith, said 130

magazine section having a movable bottom portion provided with a depressed tapered surface for guiding the ends of units of lead toward said centrally-disposed lead channel,
5 feeding means for the lead connected with said movable bottom, whereby the lead in said magazine section will be agitated to enter said lead channel, said movable bottom portion having a fulcrum, a gripping ele-
10 ment having a plurality of gripping members mounted to rock on said fulcrum, means for opening and closing said gripping members to grip and release the lead upon reciprocating movement thereof, and means for reciprocating said members to feed the lead
15 through the lead channel in a step by step movement and also to agitate leads in the magazine section.

8. A mechanical lead pencil embodying a casing having at its lower end a tapered tip 20 provided with a lead channel, a gripping element mounted to reciprocate within said casing and having a plurality of movable members adapted to close against the units of lead, and a closing element provided with a 25 plurality of resilient arms arranged to close over the members of said gripping element to produce a resilient grip on the lead, means for slidably moving said gripping and closing elements together in an interengaged 30 lead-feeding movement, and means for releasing said resilient closing member from the gripping element to release the lead.

In witness whereof, I have signed my name to the foregoing specification. 35

ABRAHAM POLLAK.
